UNITED STATES PATENT OFFICE

2,519,654

WASHING MACHINE FOR BEARINGS

William B. Heaney, Phoenix, Ariz.

Application July 23, 1945, Serial No. 606,609

2 Claims. (Cl. 134—103)

1

The present invention relates to improvements in a washing machine for bearings, and its principal object is to provide a simple device whereby bearings or the like may be cleaned thoroughly and expeditiously, and with comparatively little effort.

More particularly it is proposed to provide a machine of the character described in which a liquid-cleaning medium is forced through the bearings or agitated about the bearings by means of air pressure.

It is further proposed to provide a mounting means for the bearing whereby the latter is confined in an annular passage, so that liquid or air forced through the passage is made to pass through the bearing with the desired cleaning effect.

Further objects and advantages of my invention will appear as the specification proceeds, and the novel features of my cleaning machine will be fully defined in the claims hereto attached.

The preferred forms of my invention are illustrated in the accompanying drawing forming part of this application, in which:

Figure 1 shows a vertical section through one form of my cleaning machine; and

Figure 2, a vertical section through a modified form of my cleaning machine.

While I have shown only the preferred forms of my invention, it should be understood that various changes or modifications may be made within the scope of the claims hereto attached without departing from the spirit of my invention.

Referring to the drawing in detail, and particularly to the form shown in Figure 1, my invention comprises a tank 1 of suitable height and formed with a partition 2 substantially intermediate its height, whereby the tank is divided into an upper chamber 3 and a lower chamber 4.

The tank has a removable cover or lid 5 which may be secured upon the tank in any suitable manner.

The partition has one or more cups 6 mounted thereon, the cups being formed with spherical or conical side walls expanding from the bottom toward the top. These side walls are adapted to have bearings of various sizes seated thereon in the manner shown in Figure 1.

The bearings are held in place by upper members 7 which seat in the holes of the bearings and are secured in any suitable manner, as by rods 8 projecting radially to rest on the rims of the cups, and to be held in place by springs 9.

It is apparent that the upper members may be secured in any other suitable and preferred man-

ner, and that for different sizes of bearings, different holding members may be provided.

In this manner the bearings are firmly supported between the walls of the cups and the holding members, and the cups and the holding members form an annular passage in which each bearing is mounted.

This annular passage is connected to the lower chamber by means of a port 10 extending downwardly from the bottom of each cup.

Air may be admitted under pressure through a conduit 11 controlled by a valve 12, and terminating, near the bottom of the tank, in a spiral 13 substantially coextensive with the size of the tank and spaced slightly from the bottom thereof.

The spiral 13 is formed with a large number of apertures 14 through which air may escape into the liquid. In this manner, air bubbles may be made to rise throughout the tank area for agitating the liquid.

The rising air bubbles pass through the ports 10 and the bearings, and agitate the cleaning fluid about the same, so as to effect a thorough cleaning of the bearings.

An outlet 15 for the air is provided at the upper end of the upper chamber, and is controlled by means of a valve 16.

The bottom of the tank may be made concave, as shown at 17, to form a sump, into which dirt and impurities may collect to be discharged through a drain pipe 18, having a valve 19.

In operation, the bearings are first placed in the respective cups and secured in place by means of the holding members 7. The tank is then filled with a cleaning fluid up to a height above the bearing holding cups, as shown in Figure 1.

Next, compressed air is introduced through the pipe 11, by opening the valve 12, and the rising air bubbles are forced through the port 10 and the bearings, agitating the liquid about the same for cleaning the bearings.

In the form shown in Figure 2, a somewhat different principle is employed. The tank and the mountings for the bearings may be substantially the same as in the form previously described, but the ports 10 connect into conduits 20 extending downwardly into the lower chamber to a point near the bottom thereof.

Air is admitted into the lower chamber through a pipe 21 controlled by a valve 22, the pipe 21 preferably entering in the upper portion of the lower chamber.

A similar pipe 23 is provided to admit air under pressure into the upper chamber, and this pipe

is controlled by a valve 24. An air outlet 25 is furnished in the top of the tank and is controlled by means of a valve 26.

A similar air outlet may be provided in the upper portion of the lower chamber.

In this form of my invention all of the liquid is forced through the bearings. After the bearings have been positioned in the manner previously described, and the tank has been filled with liquid, at least to the height of the partition, as shown in Figure 2, the valve 22 is opened and air is admitted into the lower chamber under pressure.

The air forces the liquid level down, and causes the liquid to pass, under pressure, through the conduits 20 and the passages accommodating the bearings, with the desired cleaning effect.

After the lower chamber has been emptied, the air will discharge through the conduits 20 and the bearings into the upper chamber.

In case too much air should remain in the lower chamber, a special outlet pipe may be arranged for the same.

The process may now be reversed by closing the valve 22 and opening the valve 24, which forces the liquid to pass through the bearings in reverse direction. This process may be repeated until the bearings are thoroughly cleaned.

I claim:

1. In a washing machine for bearings and the like, a tank for holding a cleaning liquid, a flat, horizontal partition mounted in the tank substantially midway of the height thereof so as to divide the tank into an upper and a lower chamber of substantially the same size, a top closure for the upper chamber, a cup member mounted on the partition and having a flaring side wall adapted to have a bearing seated thereon, means for seating the bearing on the cup

member shaped to close the hole in the bearing, a tube connecting the bottom of the cup member with the lower portion of the lower chamber, means for admitting a pressure medium into the lower chamber for forcing the liquid through the tube and the bearing from below, and means for admitting a pressure medium into the upper chamber for forcing the liquid through the bearing and the tube from above.

10 2. A washing machine as defined in claim 1, in which the cup member has spring fingers operable for releasably holding the bearing seating means.

WILLIAM B. HEANEY.
